(57) **CLAIM**

The ornamental design for a fishing lure, as shown.

DESCRIPTION

FIG. 1 is a perspective view of the fishing lure showing my new design;

FIG. 2 is a bottom plan view of the fishing lure of FIG. 1;
FIG. 3 is a side view of the fishing lure of FIG. 1; and,
FIG. 4 is another perspective view shown in general assembly
for operation.

The broken line showing of environment in FIG. 4 is for
illustrative purposes only and forms no part of the claimed
design.
